Primary Examiner — Wan Laymon*Assistant Examiner* — Clint A Samuel(74) *Attorney, Agent, or Firm* — Scott T. Griggs; Griggs Bergen LLP(57) **CLAIM**

The ornamental design for a two-headed toothbrush, as shown and described.

DESCRIPTION

FIG. 1 is a front top perspective view of a two-headed toothbrush;

FIG. 2 is an enlarged front top perspective view of the two-headed toothbrush shown in FIG. 1;

FIG. 3 is a front elevation view of the two-headed toothbrush shown in FIG. 1.

FIG. 4 is a rear elevation view of the two-headed toothbrush shown in FIG. 1;

FIG. 5 is a top plan view of the two-headed toothbrush as shown in FIG. 1;

FIG. 6 is a bottom plan view of the two-headed toothbrush as shown in FIG. 1; and,

FIG. 7 is a right side elevation view of the two-headed toothbrush as shown in FIG. 1, which includes left-right symmetry.

The dashed and dotted lines shown are provided for environment purposes only and form no part of the claimed design.

1 Claim, 6 Drawing Sheets(56)
